UNITED STATES PATENT OFFICE.

FRANK FUNKE, OF INDEPENDENCE, MISSOURI.

AUTOMATIC SWITCH.

1,186,473.

Specification of Letters Patent.

Patented June 6, 1916.

Application filed September 17, 1910. Serial No. 582,468.

To all whom it may concern:

Be it known that I, FRANK FUNKE, a citizen of the United States, residing at Independence, in the county of Jackson and 5 State of Missouri, have invented new and useful Improvements in Automatic Switches, of which the following is a specification.

This invention relates to automatic circuit controllers and automatic switches for use 10 in connection with sparking circuits of internal combustion engines.

The object of the invention is to provide a switch which will automatically cut out the battery circuit when the engine has attained 15 a predetermined speed, sufficient to cause the cut-out magnet to operate through the generator circuit and whereby upon any rupture of the generator circuit or any accident to the generator, the battery circuit 20 will be automatically completed.

A further object of the invention is the provision of means included in the switch circuit for indicating the condition of the battery circuit and the generator circuit.

25 Further objects of the invention will appear as the following specific description is read in connection with the accompanying drawing which forms a part of this application, and in which:

30 Figure 1 is a top plan view of the preferred form of switch, and Fig. 2 is a diagrammatic view of the circuit employed.

Referring more particularly to the drawing 35 1 represents a base upon which is mounted a suitable switch 2 provided with a terminal binding post 3 which is connected in series with the battery B. The opposite side of the switch is connected by means of a conductor 4 to one side of a signal lamp

40 L whose opposite side is connected by means of a conductor 5 to a contact 6 which is normally engaged by a switch lever 7 operated by a spiral spring 8 and pivoted upon the vertical standard 9 carried by the base.

45 The switch lever is connected by a conductor 10 to the opposite side of the battery B. This switch lever is constructed of magnetic material and is provided with a non-magnetic stud 11 in its end so as to prevent sticking to the core 12 of the magnet 13. The magnet 13 is included in the circuit with the magneto and an independent circuit 50 14 is connected to the magneto terminals

and, consisting of a part of the battery circuit, includes a spark gap 15 and a spark 55 coil 16. The magnet 13 is adapted to act upon the switch lever 7 and withdraw from the contact 6 to break the battery circuit.

While I have not shown the connection of the battery and generator circuits with the 60 timer, it will be clearly understood by those versed in the art that the timer is connected in the circuit shown, in the usual manner. When the switch 2 is thrown to complete the battery circuit, the lamp L is lighted 65 and remains lighted until the engine attains a speed sufficient to cause the magneto or generator to energize the magnet 13 at which time the switch lever 7 is withdrawn from the contact 6, thus breaking the bat- 70 tery circuit and putting out the lamp. This indicates that the generator is operating to supply the spark plug with a sufficiently hot spark to ignite the fuel. If the generator should become accidentally broken or the 75 generator circuit ruptured, the magnet will fail to operate and the switch lever 7 released and the battery circuit thus automatically completed. I have shown a sparking arrangement 15 consisting of two separate 80 points and a coil 16 included in the generator and battery circuits, but any form of sparking arrangement may be controlled by this system so that when the engine has attained sufficient speed to give the magnet a 85 proper amount of current the battery circuit will be broken and when the generator is stopped or broken, the magnet will be re-energized and the battery circuit completed to the sparking arrangement. 90

Having thus described the invention, what is claimed is—

In a device of the kind described, in combination a battery, a generator, an electromagnet, a pair of conductors, connecting 95 said electromagnet in circuit with said generator, a conductor leading from one side of said battery to said generator, an igniter, a conductor leading from one of the conductors of said battery and connected to said 100 generator a spring pressed switch lever adapted to be drawn over against said magnet when the latter is energized, a conductor leading from the opposite side of said battery toward said switch, a contact point 105 engaged by said switch and connected to

said last-named conductor, a lamp included in said last-named conductor circuit, a contact point connected with said switch lever and to said igniter and generator connecting conductor, said switch lever normally connecting said contact point to maintain said battery circuit in a normally closed position whereby to illuminate said lamp, and

a manually controlled switch for breaking said battery circuit.

In testimony whereof I affix my signature in presence of two witnesses.

FRANK FUNKE.
